(57) **CLAIM**

The ornamental design for a food mat, as shown and described.

DESCRIPTION

FIG. 1 is a perspective view of a food mat showing our new design;

FIG. 2 is a top plan view thereof;

FIG. 3 is a front view thereof, the back view being identical;

FIG. 4 is a sectional view taken along line 4-4 of FIG. 2;

FIG. 5 is a bottom plan view thereof;

FIG. 6 is a right side elevation view thereof, the left side elevation being identical; and,

FIG. 7 is an enlarged detail view of the area labeled "7" in FIG. 4.

The broken lines and the areas within the broken lines in the drawings depict portions of the article that form no part of the claimed design.

1 Claim, 4 Drawing SheetsFIG. 6

FIG. 5

FIG. 7
